Attorney S.

UNITED STATES PATENT OFFICE.

JAMES H. WILLIAMS, OF BALTIMORE, MARYLAND.

PIANO.

1,424,606.

Specification of Letters Patent. Patented Aug. 1, 1922.

Application filed July 6, 1921. Serial No. 482,719.

To all whom it may concern:

Be it known that I, JAMES H. WILLIAMS, a citizen of the United States, residing at Baltimore, in the county of Baltimore, State of Maryland, have invented certain new and useful Improvements in Pianos; and I do hereby declare the following to be a full, clear, and exact description of the invention, such as will enable others skilled in the art to which it appertains to make and use the same.

The object of the invention is to provide a sound board supporting frame for pianos, whereby the volume and duration or sustaining quality as well as the breadth of the tone are increased by amplifying the agencies responsive to vibrations received by the sound board from the strings, and more especially in providing supplemental tone responsive agencies which are particularly sensitive to the overtones and harmonics, which under ordinary circumstances, are lost after a brief period, through the predominance of the fundamentals or basic tones to which the frame itself is ordinarily more directly responsive and hence, by prolonging the vibrations which represent the overtones and harmonics, maintaining the richness and fullness of each tone substantially throughout the duration of the vibrations representing the fundamental or basic tones; and with this general object in view, the invention consists in a construction, combination and arrangement of elements of which a typical embodiment is illustrated in the accompanying drawings with the understanding that changes in form, proportions and details may be resorted to in adapting the invention to different makes and types of musical instruments, without departing from the principles involved.

In the drawings which are designed more particularly to show the application of the invention to the upright piano structure,

Figure 1 represents a front or inside view of the sound board supporting frame of a standard form of instrument.

Figures 2 and 3 are horizontal sectional views of the same on the planes, indicated respectively by the lines 2—2 and 3—3 of Figure 1.

Figures 4 and 5 are vertical sectional views of the same, respectively on the planes indicated by the lines 4—4 and 5—5 of Figure 1.

Figures 6 and 7 are enlarged detail sectional views on the planes indicated respec-

tively by the lines 6—6 and 7—7 of Figures 4 and 5.

Figure 8 is a view of a sound board frame corresponding with Figure 1, wherein diagonal braces are employed in addition to the vertical bracing or filler members.

Figures 9 and 10 are horizontal sectional views, respectively on the planes indicated by the lines 9—9 and 10—10 of Figure 8.

Figure 11 is a detail view in perspective of one corner of the sound board supporting frame.

The sound board supporting frame which has been selected as a means of illustrating the invention consists of marginal upper and lower members 20 and 21 and marginal side members 22 and within this marginal frame, in the form shown in Figures 1 to 7 inclusive, are arranged the upright bracing or filler members 23, usually arranged in spaced relation as shown, and in intersecting relation with the upper and lower members 20 and 21, the front surfaces of the bracing or filler members, however, being set back slightly from the plane of the corresponding surfaces of the marginal members so that the sound board 24 which rests upon and is secured to the marginal members of the frame is intermediately out of contact with the bracing or filler members and hence is free to vibrate. The edges of the sound board also may be and are preferably spaced slightly from adjacent abutting objects, such as the casing, in which the frame is housed, so as to avoid any tendency to bind or interfere with the freedom of vibration of the sound board.

The marginal frame members are provided with channels 26 extending longitudinally thereof with their extremities stopped or interrupted to prevent communication with the atmosphere and hence to prevent loss of longitudinal vibration of air confined in said channels through open ends thereof, and while preferably the ends of the channels in intersecting marginal members are in communication, as clearly shown in Figure 1, it will be understood that, whereas in the construction illustrated, these longitudinal channels of the marginal frame members are formed in all four of said members, that is to say, both the upper and lower and both side members, modifications of this arrangement may, under certain circumstances, be adopted or found preferable as, for example, omitting the channel in the upper marginal member to the end that the otherwise con-

tinuous channel formed in the lower and side members terminates at or near the upper ends of the side members as, for example, at or about the dotted line *a—a* in Figure 1.

5 Furthermore, the bracing or filler members 23 are likewise provided with longitudinal channels 27, which may be and preferably are in communication terminally with intersecting channels in the marginal members. Whereas the channels 26 of the 10 marginal members, however, are covered and closed by the sound board, as shown in Figures 2 to 5, inclusive, in the construction illustrated, and whereas the sound board constitutes the outer or front wall of 15 these channels in the marginal frame, the front walls of the channels in the bracing or filler members 23, due to the fact that said members are spaced from the plane of 20 the sound board, are provided with thin walls 28, consisting of strips of wood held in place by glue or like adhesive material and exposed directly to the effect of the 25 vibrations of the sound board through the agency of the intervening layer of air due to the spaced relation above mentioned. Moreover, whereas the channels in the marginal members are provided with lateral 30 vents or outlets 29, designed to permit of the communication of vibrations of the air set up or communicated thereto by the sound board to the enclosed columns of air in the channels 26, the channels in the bracing or filler members 23 are provided with 35 vents or outlets 30, preferably formed in the front or outer thin wall 28, so as to be in direct facing relation with the sound board as a means of providing for the communication of vibrations communicated 40 through the interposed layer of air between the sound board and said bracing members to the columns of air in the channels 27 through the openings or vents 30 as well as 45 through the relatively thin walls formed by the strips 28.

In the construction illustrated, there is provided, in addition to the channels above described, what may be termed for convenience a supplemental or auxiliary, depressed 50 channel 31 formed in the marginal frame (including, for example, the upper and lower and both side members) which is arranged in a plane parallel with the channels hereinbefore described as being formed in the marginal and filler members, said auxiliary or 55 depressed channel being in communication with the channels 26 in the side marginal members by vents or openings 32, and a thin partition wall 33 being interposed between 60 said channels 31 and 26. And when this construction is followed, the side marginal members are preferably of sectional construction and embody the main or base sections 22^a and strips or supplemental sections 22^b which latter rest upon the partition

walls 33. When this construction of tiered or a plurality of parallel channels is employed, the extremities of the channels 27 in the bracing or filler members 23 preferably communicate with the supplemental or depressed channel 31, or the portions of said channel which traverse the upper and lower members of the marginal frame as will be clearly noted by reference particularly to Figure 5.

75 It will be noted, however, that the extremities of the channels 31 formed in the marginal members are stopped longitudinally although in communication with the portions of the channels formed in the intersecting members of the marginal frame so that whereas there is what may be termed a continuous channel 31 extending through the top, bottom and side members of the marginal frame, parallel with the plane of 80 the channels 26, the only vents or outlets from said channel are lateral and therefore that there is provision for a longitudinal responsive vibration of the columns of air in the several communicating portions of the 85 channel. There is also responsive vibration of the air in the channels 27 of the bracing or filler members and the columns of air in the channel 31, or the portions thereof with which said channels 27 communicate and 90 which said channels 27 communicate and 95 there is responsive vibration communicated through the vents or openings 32 between the columns of air in the portions of the channels 26 formed in the side members of the marginal frame and the channels 31 100 which are located beneath and in parallelism therewith.

Moreover, in the modified construction illustrated in Figures 8 to 10, inclusive, where the diagonal corner bracing or filler 105 members 33 are added to the upright bracing or filler members 23^a, channels 34 are provided, to be covered by the sound board and having terminal communication with the channel 26^a, corresponding in arrangement with the channel 26 shown in Figures 1 to 7, inclusive, and provided at the surfaces of the marginal frame members. In other respects, inclusive of the depressed channel 31^a, the construction illustrated in 110 Figures 8 to 10, inclusive, corresponds with that which was previously described and the channels 27^a of the upright bracing or filler members are covered by the thin walls 28^a, which are spaced from the adjacent surface of the sound board 24^a and are provided with the openings or vents 30^a.

115 What is claimed is:

1. A piano having a marginal sound board supporting frame of which the members are provided, in planes parallel with the sound board, with a plurality of longitudinal channels arranged at different distances from the plane of the sound board.

120 2. A piano having a marginal sound 130

board supporting frame of which the members are provided in planes parallel with the sound board, with a plurality of longitudinal terminally stopped channels disposed at different distances from the plane of the sound board.

3. A piano having a marginal sound board supporting frame of which the members are provided in planes parallel with the sound board, with a plurality of longitudinal terminally stopped channels disposed at different distances from the plane of the sound board, the corresponding channels in intersecting members of the frame being arranged in terminal communication.

4. A piano having a marginal sound board supporting frame of which the members are provided in planes parallel with the sound board, with a plurality of longitudinal terminally stopped channels disposed at different distances from the plane of the sound board, said channels being transversely in communication.

5. A piano having a marginal sound board supporting frame of which the members are provided in planes parallel with the sound board, with a plurality of longitudinal terminally stopped channels disposed at different distances from the plane of the sound board; said channels being transversely in communication at spaced points.

6. A piano having a marginal sound board supporting frame of which the members are provided in planes parallel with the sound board, with a plurality of longitudinal terminally stopped channels disposed at different distances from the plane of the sound board, said channels being separated by relatively thin walls.

40 7. A piano having a marginal sound board supporting frame of which the members are provided in planes parallel with the sound board, with a plurality of longitudinal terminally stopped channels disposed at different distances from the plane of the sound board, one of said channels being laterally closed by the sound board.

8. A piano having a sound board supporting frame including marginal and filler members of which the former have surface and depressed parallel channels extending longitudinally thereof and of which the latter have channels extending longitudinally thereof and in terminal communication with one of the channels in the intersecting marginal members.

60 9. A piano having a sound board supporting frame including marginal and filler members of which the former have surface and depressed parallel channels extending longitudinally thereof and of which the latter have channels extending longitudinally thereof and in terminal communication with one of the channels in the intersecting marginal members, the filler members being ar-

ranged with their channelled faces in spaced relation with the plane of the sound board.

10. A piano having a sound board supporting frame including marginal and filler members of which the former have surface and depressed parallel channels extending longitudinally thereof and of which the latter have channels extending longitudinally thereof and in terminal communication with one of the channels in the intersecting marginal members, the surface channels of the marginal members being covered and closed by the sound board and the filler members having their channelled faces spaced from the plane of the sound board and covered by relatively thin walls.

75 11. A piano having a sound board supporting frame including marginal and filler members of which the former have surface and depressed parallel channels extending longitudinally thereof and of which the latter have channels extending longitudinally thereof and in terminal communication with one of the channels in the intersecting marginal members, the surface channels of the marginal members being covered and closed by the sound board and the filler members having their channelled faces spaced from the plane of the sound board and covered by relatively thin walls, with spaced perforations formed in said walls.

80 12. A piano having a sound board supporting frame, including marginal and filler members of which the former are provided with surface and depressed parallel channels extending longitudinally thereof and of which the latter are provided with surface channels terminally communicating with the depressed channels of the intersecting marginal members and covered by relatively thin walls.

85 13. A piano having a sound board supporting frame, including marginal and filler members of which the former are provided with surface and depressed parallel channels extending longitudinally thereof and of which the latter are provided with surface channels terminally communicating with the depressed channels of the intersecting marginal members and covered by relatively thin walls, having perforations arranged at spaced points therein.

90 14. A piano having marginal and filler members of which the former are provided with surface and depressed parallel channels extending longitudinally thereof and the latter are provided with surface channels terminally communicating with the depressed channels of the marginal members, and having thin channel covering walls facing and in spaced relation with the sound board.

In testimony whereof, I affix my signature.

JAMES H. WILLIAMS.
